Mr. Bradford -

Attorney

Patented May 17, 1927.

UNITED STATES PATENT OFFICE.

LORAN ISBELL, OF LITTLE YORK, NEW YORK.

SNOWPLOW.

Application filed July 28, 1925, Serial No. 46,644. Renewed April 14, 1926.

My invention relates to snow plows of the dirigible type adapted to clear the bulk of snow from a roadway, which plow is readily attachable to a conventional truck, tractor or other motor propelled vehicle, and embodies certain novel structural features together with improved control devices for properly meeting varying service contingencies.

10 The preferred embodiment of my plow comprises a rugged structure or frame work carrying a transversely disposed frame plow blade; the propulsive effort required to operate such cutting element is furnished by the vehicle motive power and this drives the blade under the body of snow or, if need be, breaks up blocks of partially frozen ice that may come within the path of plow travel. Independent snow ejecting and elevating equipment is provided to lift the plowed snow above the level of the snow bed and to discharge the same over to a side of said path; if desired, the snow may be conveyed still higher into trucks to be 25 hauled away.

An important object is therefore to provide necessary means for plowing through a relatively deep snow bed and accomplish the purposes indicated. To this end, my 30 front or bottom cutting blade is preferably equipped with a scoop plate mounted rearwardly thereof in an upwardly inclined relation. An upright mold-board is carried by such sloping plate and these cooperating 35 guide elements are purposely so shaped as to shift and divert the plowed snow sidewise of the structure. The mold-board preferably comprises a section that extends across said plate in an oblique relation with respect 40 to the cutting edge of said transverse plow blade.

In order to expedite the movement of the plowed snow along said guide elements and otherwise facilitate the delivery of snow 45 over the structure side, I provide for an obliquely disposed conveyor or other suitable snow ejector device preferably running lengthwise of and adjacent to said board section, which device is adapted to pick up 50 and remove the plowed snow from the scoop plate. When such guide elements are used alone that it is to say without said conveyor means, the snow cannot be induced to readily move therewithout applying an inordinate amount of tractive effort to propel the plow onward because snow does not

scour well and the snow plowed from the cleared path must be pushed aside and rolled over onto or otherwise packed into the bordering snow bank. I have found, 60 however, that such excessive plow resistance may be reduced to a marked degree by resorting to a power driven conveyor capable of lifting and at the same time facilitating the movement of snow in the direction initially imparted to it by the mold-board shape; in addition, such positive ejector means allow of more readily elevating the snow to any higher level that may be 65 needed for loading or similar purposes. 70

Another object of this invention is to provide means whereby said plow blade may be properly guided with respect to the road bed contour. The blade is preferably supported by a pair of spaced runners and 75 interposed means are provided for conveniently altering the height of the blade relative to said runners, the necessary adjustments being made through distant control means operable from the vehicle seat and 80 adapted to leave a predetermined depth of snow on the ground after the passage of the plow structure and the front of the propelled vehicle. The drive coupling means provided between the plow frame and the 85 truck is intended to function in the manner of a universal joint and may consist of a single drive stanchion loosely engaging the frame member to allow of tilting the plow structure about said pivotal connection either 90 laterally or vertically with respect to the tractor drive means.

It is preferred to mount my plow structure on a three point support basis in order 95 to obviate teetering tendencies with respect to the road bed; the pair of forwardly disposed runners may constitute two elements of such a support while the rear of the structure is carried upon the drive stanchion and is indirectly supported by the road bed 100 through the medium of the front vehicle wheels. The vertical adjustment for the runner end of my plow structure is afforded by the aforesaid separate blade lifting or lowering devices while the height of the 105 rearward structure portion may be independently altered through the use of suitable support collars or the like, associated with said stanchion.

The steering mechanism is designed to 110 swerve the plow structure bodily about said drive stanchion as a fulcrum connection,

thereby selectively throwing and positively holding the plow blade in any desired skewed relation with respect to the longitudinal axis of the propelling vehicle. For 5 steering purposes, I preferably employ a control device of the windlass type, this being adapted to actuate a pair of complementary chains or other tie means respectively attached to the opposite sides of the plow 10 structure. The windlass may readily be mounted upon the vehicle within convenient reach of the driver's seat and by manipulating said steering mechanism, one of said frame ties may be drawn toward the windlass while the other is being released so as 15 to effect a skewed sidewise movement between the plow and the vehicle.

My plow may further be equipped with a side cutting blade preferably disposed near 20 one end of the bottom cutting blades and attached to the front end of the upright mold-board. Should it be desired to remove snow from the side of a deep beaten road path or partially cleared snow drift and to 25 throw the snow over to the other side of the roadway, the plow may then be skewed around and kept headed into said bank, whereupon the side cutting blade will become effective while the steering devices 30 hold the plow structure in proper position against the lateral thrust imposed by said side cutting blade; likewise, in the event that either set of tractor wheels should tend to slide off of the road, my steering means still 35 enables the driver to get the tractor back on the road without having the plow unduly interfering therewith.

My universal steering controls provide a 40 fully dirigible plow organization that allows not only of making sharp turns in the roadway, but also enables the plow and its tractor to adjust themselves readily for properly plowing over road ruts, raised crosswalks or similar road irregularities, all 45 without throwing the blade out of the plowed snow bed, causing the plow to dig into the road bed, stalling the propelling vehicle, or otherwise imposing undue strain or danger of breakage to plow parts.

50 The present invention also includes certain other features of structure and organization, all of which will be pointed out in detail hereinafter.

Reference is had to the accompanying two 55 sheets of drawings which are illustrative as an example of a specific embodiment of my invention; like characters of reference indicate like parts in the several views, in which drawings,

60 Figure 1 is a plan of my device,
Figure 2, a side elevation.

Figure 3, a detail of attaching means for securing it to a truck,

65 Figure 4, a detail of the adjusting means for the front end of the plow, and

Figure 5, a similar view showing the adjusting means for the rear end of the plow.

Reference character 10 indicates a suitable chassis cross member of a truck supported by an axle 11 on wheels 12 at its forward 70 end. The bent member 10 is preferably provided with a pair of braces 13 secured thereto by means of depending arms 14, these braces being also attached to vehicle springs 15 from which the shackle bolts have been 75 removed and replaced with longer bolts 16. These braces support a bar 17 having upwardly extending bearings 18 in which a windlass drum rod 19 is mounted. A pair of links 20 may be supported at one end by 80 the bolts 16 and at the other end pass between bar 17 and rod 19, the latter ends being enlarged and provided with openings for a vertically disposed drive stanchion 21 passing at its upper end through a bracket 85 22 fixed to the frame member 10.

The stanchion 21 carries an adjustable collar 21^a secured thereto by a set screw 21^b as shown in Figure 5 which forms the rear support for the frame work structure of the 90 plow and this frame may be connected to said stanchion through a pair of diverging angle irons 23 adapted to loosely embrace said stanchions at their crutch so as to constitute a single flexible drive coupling for the 95 plow. If desired the forward ends of said irons may be tied together by a cross-bar or other suitable means and secured thereto is a transversely disposed plow blade 41.

Near said angle iron ends, I provide for 100 pintles 24 on which shoes 25 or other suitable runner means are pivoted, and it will be observed that these spaced pintles are disposed directly under and closely adjacent to the forward or bottom cutting edge of 105 the substantially rectilinear plow blade 41 while the free shoe end is rounded upward to constitute a heel element 25'.

These pivoted shoes 25 provide means 110 whereby the frame may be adjusted vertically to determine the depth of the snow to be left by the plow. For this purpose a pair of interposed toggle links 26 may each be pivoted at one end to cooperate with each other and with a runner 25 and at the other 115 end to one of a pair of nuts 27 on a threaded rod 28. Each one of a pair of links 29 may similarly be pivoted to a rigid member 30 of the frame structure here shown as a short cross bar between two bars 31 and 32 extending lengthwise of the plow. These links are further shown as pivoted also to nuts 27, the whole forming a double toggle which is duplicated at the other side of the plow to constitute a self-locking lifting device, 125 and which toggles may under certain contingencies be increased or decreased in number according to the width of the plow and the work to be done. Rods 28 may each be equipped at their respective rear ends 130

with a universal joint 33 which connects to the extensible shaft 35 having an intermediate tubular slip-joint 35^a provided with a slotted drive key 35^b, and these two complementary shafts 35 may be simultaneously rotated by means of the universal joint 34, shaft 36, worm gearing 37, and shafts 38, 40 and also 39 which latter shaft or rod is made extensible and provided with a slip joint 39^a of the keyed type similar to joint 35^a adapted to compensate for its offset rod relation with respect to the frame drive pivot 21; all these interconnected adjusting members are controlled and operated 10 from a hand wheel or other suitable centralized control device by means of which the lead of the blade of the plow or its distance above the road bed may be altered by raising and lowering the front of the frame in the fashion indicated in Fig. 4 by dotted lines. By this device any amount of snow can be left on the highway so as to comply with state, county, or town laws. The worm gearing operable from the vehicle seat may 20 be relied on to maintain the desired adjustment but it will be apparent that other suitable means may be used. It will further be evident that the placing of the runner hinge directly under the substantially straight 25 plow blade as described, permits the rear of the frame structure to be raised or lowered without perceptibly altering the desired fixed distance of the blade edge with respect to the road bed and which further minimizes 30 the vertical plan blade movement when the vehicle is obliged to travel over road irregularities.

The frame is preferably provided at its forward end with a dentate cutting blade 41 40 which serves to more readily break up ice and hard packed snow that might otherwise resist the action of a merely straight blade edge on the plow. A snow ejector device capable of carrying off the snow to one side 45 of the plow structure, may be mounted on this framework at an oblique angle with respect to the transverse cutting edge of the plow blade and it is pointed out that this characteristic conveyor disposition represents 50 an important feature of the present invention. Said conveyor means may be located on the frame toward the left-hand side of the plow reaching rather close up to the blade and slanting backward across the 55 frame, and as here shown, comprises a conventional endless belt or band loop 42 of any suitable material moving on suitable rollers or pulleys. Such ejector means may be equipped with suitable sweeping cleats 60 adapted to pick the plowed snow off the scoop plate 48; to this end, the major portion of said belt loop may be mounted beneath the level of said plate 48 while the upper belt length is made to ride over the 65 top face of said plate in the fashion indi-

cated. The belt is shown as provided with sprocket chains 43 at the sides passing over sprocket gears, one of which is driven by a chain 44 running over a sprocket gear on a shaft driven by a motor 45, such for instance as an electric motor, or an internal combustion engine or any other suitable device preferably operated entirely independently of the motive power used for vehicle propulsion. Said coupling together 70 with its motor is arranged to be swerved about said single pivotal drive coupling and to maintain a fixed relation with respect to the cutting edge of the plow blade.

Mounted upon the frame structure is a 80 scoop plate 48 that extends rearward in an inclined relation from the transversely disposed bottom blade 41 and the snow is intended to be shoved back therealong toward the conveyor by the plowing operation. 85 Mounted adjacent to the rearmost side of said obliquely disposed conveyor chain and extending substantially upright out of the plate 48 is a mold-board section 46 of which the forward portion is sharply directed ahead so as to terminate in a side blade element 47, preferably located near one end portion of the bottom cutting blade as shown in Figure 1. The other extremity 90 of the mold-board 46 may be extended rearward beyond the side of the frame structure while the scoop plate 48 may be equipped with a coating guard or wing portion 49 adapted to facilitate the delivery of the snow into the conveyor and prevent needless 95 spilling over the structure side. It is emphasized that said mold-board and scoop plate are preferably so shaped that the plowed snow is thereby made to move rearward from the blade and gradually directed 100 sidewise of the structure. In the present invention, the conveyor may be considered as constituting a supplementary accelerating means adapted to expedite the inherently 105 slow primary movement which the described plow assembly is of itself capable of imparting to the snow were recourse not had to such auxiliary conveying means. It is intended that the conveyor drive 45 should be operated at a speed that will freely remove 110 all the snow delivered to it by the plow blade; as a result, the resistance to rearward movement by the plowed snow is greatly reduced over that required were the receding snow obliged to squeeze directly into the 115 side of the bordering cleared snow bank.

Steering mechanism for the device includes a steering post 50 preferably mounted upon the vehicle and operable from the driver's seat and this may be connected by 120 means of a worm 51 on the post and a worm wheel (not shown) mounted on the windlass device 19 so as to turn its drum in one direction or the other, serving to pull up on one of the two chain tie means 52 and let off 130.

the other 53, thereby swerving the plow side-
wise with respect to the vehicle. The re-
spective chains may be yieldably attached to
opposite sides of the frame structure so as
6 to cushion shocks and permit limited rela-
tive movement between the truck and the
plow by means of eye bolt rods 55 passing
through supports 56 and having springs 57
surrounding the rods at the other side of
10 said supports. Preferably these rods are
each made in two parts connected by a turn-
buckle 58 for purposes of adjustment.

It is desired to call particular attention
15 to the three-point support for the device
comprising the drive stanchion carried by
the truck frame and the adjustable shoes 25
pivoted to the front corners of the plow
structure so as to afford proper lateral sta-
bility for the plow frame about its single
20 pivotal drive coupling. This improved dis-
position permits the plow to rock so as to
maintain a uniform distance from the road
and this is true whether the road is a narrow
dirt road or a wide road of cement or as-
25phalt. Another feature of importance re-
sides in the fact that this device leaves the
road in an unusually smooth condition due
to placing the spaced shoe supports at the
extreme front of the plow and directly under
30 the blade 41, since similar smoothness cannot
readily be secured by devices supported at a
distance from the front end of the plow.

It should also be noted that the attachment
35 of the frame of the plow directly to the
frame of the truck makes it possible to at-
tach a steering device in such a manner that
it will be free from jars and shocks which
it would receive if attached to the front axle.

The stanchion 21 is so located by means of
40 the bracket 22, (which may be a U-bolt se-
cured to the frame member 10 by means of a
pair of holes through said frame member)
and by means of links 20 as to provide a
considerable space for adjustment of the rear
45 of the plow structure in a vertical sense. It
is contemplated that the distance over which
such rear frame adjustment shall be made
might be as much as a foot or more, and it
will be evident that adjustment of the rear
50 end of the plow will correspondingly vary
the height of the delivery end of the con-
veyor, thereby permitting the snow to be
ejected from the plow at greater or less eleva-
tion according to the depth of snow at the
55 sides of the plowed path, the point of snow
delivery being generally kept at from about
thirty to forty inches above the road or street
level.

It will be understood that the device of
60 my invention can also be used for removing
the snow from the road and piling it up at
the sides thereof or it can be used effectively
for removal and handling of snow by load-
ing it on cars or trucks following alongside
65 the plow. This is one reason for the ad-

justment of the point of snow delivery since
obviously that point will need to be higher
when the delivery is made to a truck than
when the snow is merely discharged at the
side of the road.

Another purpose of the described plural
controls is to offset side slipping of the plow
propelling vehicle when driving along-
side the crown of a road. Such controls
also permit the crossing of narrow bridges
70 constructed or located at a curve in the road
and likewise permit clearing of a space
outside a beaten path while said vehicle
remains on firm footing on said path.
The plow illustrated and described has been
75 found by actual tests to function efficiently
and to fully meet the exacting demands re-
quired to make up a successful implement of
this type.

It will be obvious to those skilled in the
art that my invention is susceptible of rather
wide modification without departing from
the essential underlying principles or mode
of operation, and that the disclosure of
my invention is to be considered as illus-
80 trative rather than restrictive since various
other forms may be installed in place of
the particular conveyor devices shown, and
that numerous other changes may be made
without departing from the spirit of the
85 invention, the true scope of which is suc-
cinctly set forth in the appended claims, it
being understood that the term "truck" or
"vehicle" wherever used in the specification
or claims is intended to mean any type of
90 driven vehicle appropriate for the purpose.
Having thus fully described my said in-
vention, what I claim as new and desire to
95 secure by Letters Patent, is:

1. In a dirigible snow plow adapted to
be pushed by a propelled vehicle having a
seat, a rearwardly inclined frame structure
provided at its forward end with a trans-
verse plow blade, a single pivotal drive cou-
pling disposed between the front of the
105 vehicle and the raised rear of said frame,
runner means adapted to support the plow
blade end of said structure and permit of
110 variably adjusting the height thereof with
respect to the road bed, means operable from
the vehicle seat for effecting the aforesaid
blade adjustment, and steering means includ-
ing tie means for the respective structure
115 sides adapted to positively turn said plow
structure bodily with respect to the vehicle
about said pivotal coupling.

2. In a dirigible snow plow adapted to
be pushed ahead of a propelled vehicle, a
rearwardly inclined frame structure provid-
ed at its forward end with a transverse plow
blade, a single pivotal drive coupling dis-
posed between the front of the vehicle and
the raised rear end of said frame serving
120 to support the latter and permit of variably
adjusting the height thereof, runner means
125

- adapted to support the blade end of said frame and permit of variably adjusting the height of the forward frame end independently of the aforesaid rear end frame adjustment, and steering means adapted to positively turn the plow structure with respect to the vehicle about said pivotal coupling.
3. In a dirigible snow plow adapted to be pushed by a propelled vehicle, a frame structure provided at its forward end with a transverse plow blade, a single pivotal drive coupling disposed between the front of the vehicle and the rear of said frame adapted to support the rear of said frame, laterally spaced runner means serving to support the respective end portions of said blade and permit of variably adjusting the height thereof, and means for simultaneously effecting the aforesaid adjustment at both ends of said blade.
4. In a snow plow adapted to be pushed by a propelled vehicle, a rearwardly inclined frame structure provided at its lower forward end with a transversely disposed blade, a drive coupling between the vehicle and said frame, and an obliquely disposed endless conveyor means having its delivery end raised with respect to the blade level and adapted to elevate all the plowed snow and discharge the same over one raised side of said frame structure.
5. In combination, a truck, a pivotal drive coupling on the truck, a triangular frame loosely mounted to rock on said coupling, shoes at the forward corners of the frame, a plow at the forward end of the frame, an obliquely disposed conveyor for carrying the snow toward the side of the plow, and a shield at the rear side of said conveyor.
- 40 6. In combination, a truck, a single pivotal coupling on the truck, a supporting frame mounted to rock on said pivot, shoes at the forward corners of the frame, operating means on said truck to alter the distance between the shoes and frame, a plow at the forward end of the frame, and a conveyor for carrying the snow toward the side of the plow said conveyor being inclined rearwardly and upwardly from one end of said plow.
- 45 7. In combination, a truck, a pivotal coupling on the truck, a frame structure mounted to rock on said pivot, runner-means at the forward end of the frame adapted for adjustment towards and away from said frame, a plow at the forward end of the frame, a conveyor for carrying the snow toward the side of the plow said conveyor being inclined rearwardly and upwardly from one end of said plow, and adjustable supporting means for the rear end of the frame to vary the point of discharge of the snow.
- 50 8. In a dirigible snow plow adapted to be pushed by a propelled vehicle, a plow structure provided at its forward end with a plow blade, support means for the blade, an obliquely disposed conveyor of the endless belt type serving to elevate and remove the plowed snow from the rear of said blade and adapted to deliver said snow over a frame side, a single pivotal coupling between the rear of said structure and the front of the vehicle, said coupling allowing bodily swerving of said structure sidewise with respect to the vehicle, and means operable from the vehicle adapted to steer the plow positively with respect to the vehicle about said coupling.
- 55 9. In a dirigible snow plow adapted to be pushed by a propelled vehicle, a plow structure provided at its forward end with a plow blade, runner means bearing on the road bed and adapted to support the blade end of the structure, a single pivotal coupling between the rear of said structure and the front of the vehicle, said coupling being adapted to allow tilting of said structure either vertically or sidewise with respect to the vehicle, control means operative from said vehicle adapted to raise or lower said blade adjustably with respect to said runner means, windlass means carried by the vehicle, said windlass being equipped with separate tie means respectively secured to the opposite sides of said structure, and means actuating the windlass serving to steer said structure bodily with respect to the vehicle about said coupling.
- 60 10. In a dirigible snow plow adapted to be pushed by a propelled vehicle, a plow structure adapted for three-point support with respect to the road bed and provided at its forward end with a plow blade, a pair of runners serving to support the blade and constituting two elements of said three-point structure support, a single pivotal drive connection between the rear of said structure and the front of the vehicle, said connection being adapted to allow tilting of the structure and serving as the other element of said three-point structure support, windlass means carried by the vehicle, said means being equipped with separate tie means secured respectively to the opposite side of the structure, and means for actuating the windlass serving to swerve said runners about said pivotal connection.
- 65 11. In a snow plow adapted to be pushed by a propelled vehicle, a plow structure adapted for three-point support with respect to the road bed and provided at its forward end with a plow blade, a pair of runners serving to support the blade and constituting two elements of said three-point structure support, a pivotal connection between the rear of said structure and the front of the vehicle, said connection being adapted to allow tilting of the structure upward with respect to the vehicle and serving as the other element of said three-point frame sup-

- 6 port, and lifting means interposed between said runners and the structure adapted to adjustably raise or lower the front portion of said structure bodily about its pivotal connection to the vehicle.
12. In a snow plow adapted to be pushed by a propelled vehicle, a plow structure provided at its forward end with a plow blade, runner means serving to support the 10 blade with respect to the road bed, a single pivotal connection between the rear of said frame and the front of the vehicle, said connection being adapted to allow vertically tilting of the structure with respect to the 15 vehicle, lifting means interposed between said runner means and the structure adapted to adjustably lift or lower the front portion of said structure bodily about its pivotal vehicle connection, and distant control means 20 operable from the vehicle serving to fix the adjustment of said lifting or lowering means for the purpose of altering the height of the plow blade with respect to the road bed.
13. In a dirigible snow plow adapted to be 25 pushed by a propelled vehicle, a plow structure provided at the forward end with a plow blade, a flexible drive coupling interposed between the structure and said vehicle, runner means serving to support the blade 30 with respect to the road bed, a scoop plate member mounted upon said structure and extending rearward from the blade in an upwardly inclined relation, and a snow 35 ejector device including a power driven conveyor adapted to pick up and remove said snow from the rear of said plate, said conveyor running obliquely with respect to the blade cutting edge and serving to further 40 elevate and throw the plowed snow over one side of the structure.
14. In a snow plow comprising a plow structure provided at its front end with a plow blade, a scoop plate member mounted rearwardly of said blade, and a snow ejector 45 device including a power driven conveyor having endless belt means mounted obliquely with respect to the blade cutting edge and running both under and over a portion of said plate, said belt means being adapted to 50 remove the plowed snow from the rear portion of said plate and discharge the same over a structure side.
15. In a snow plow comprising a plow structure provided with a plow blade extending 55 across the front thereof, and an endless conveyor device adapted to pick plowed snow from one end portion of the blade and carry the plowed snow in an oblique direction with respect to the blade cutting edge 60 for the purpose of elevating said snow and discharging the same over the structure side adjacent to the opposite end portion of the blade.
16. In a dirigible snow plow adapted to 65 be pushed by a propelled vehicle, a plow 70 structure provided at its forward end with a transversely disposed bottom cutting plow blade and with a side cutting plow blade, means for supporting said blades, a pivoted coupling connecting the rear of said structure with the front of said vehicle, and control means adapted to position said structure about said connection in a skewed sidewise relation with respect to the vehicle.
17. In a dirigible snow plow adapted to 75 be pushed by a propelled vehicle, a plow structure provided at its forward end with a transversely disposed bottom cutting plow blade and with a side cutting plow blade, means for supporting said blades, a pivoted 80 coupling connecting the rear of said structure with the front of said vehicle, steering means adapted to position said structure about said connection in a skewed sidewise relation to the vehicle, and an obliquely 85 disposed conveyor of the endless belt type adapted to discharge the plowed snow over the structure side.
18. In a dirigible snow plow adapted to 90 be pushed by a propelled vehicle, a plow structure provided with a side cutting plow blade, coupling means between the structure and the vehicle allowing of swerving said structure sidewise with respect to the vehicle, and adjusting means for selectively holding 95 said structure in a fixed swerved position against the side thrust imposed by said blade.
19. In a snow plow comprising a plow structure provided with a plow blade extending across the front thereof, a snow ejector device adapted to convey plowed snow from one end portion of the blade in an oblique direction with respect to the blade cutting edge for the purpose of elevating said snow and discharging the same over the structure 100 side adjacent to the opposite end portion of the blade, and means for adjustably raising or lowering the point of snow discharge with respect to the plow blade level.
20. In a snow plow comprising a plow 110 structure provided with a scoop plate means, a mold-board means associated with said plate having an obliquely disposed section, and snow ejector devices including a power driven conveyor juxtaposed to said oblique 115 board section, said conveyor serving to expedite the movement of plowed snow therealong for the purpose of minimizing the tractive effort required to propel said plow.
21. In a propelled snow plow, a snow 120 guide means including an upwardly inclined scoop plate means and a cooperating obliquely disposed mold-board, said guide means being shaped to elevate and also cause the plowed snow to be diverted 125 sidewise of the plow travel, and a power driven ejector means serving to expedite said sidewise movement of the snow along said scoop plate.
22. In a snow plow comprising a trans- 130

versely disposed blade, scoop plate means extending rearward from the blade in an upwardly inclined relation serving to elevate the plowed snow, a side cutting blade associated with one end portion of said transverse blade, mold-board means extending obliquely across said plate and adapted to direct all of the plowed snow toward the opposite end portion of the transverse blade, and power driven means serving to expedite the ejection of said snow in the general direction imparted thereto by said board.

23. In a dirigible snow plow adapted to be pushed by a propelled vehicle, a plow frame structure provided with a blade, a pivotal drive coupling means disposed between the vehicle and the frame, a power driven conveyor means wholly mounted upon said frame and serving to carry the plowed snow off toward a frame side, and means for simultaneously turning said blade and said conveyor about said coupling pivot.

24. In a dirigible snow plow adapted to be pushed by a propelled vehicle, a plow frame structure provided with a blade, a pivotal coupling means disposed between the vehicle and the frame, an endless conveyor belt means carried by said frame and disposed in angular relation to the cutting edge of said blade, and means for bodily skewing the frame blade together with the conveyor about said coupling pivot.

25. In a snow plow adapted to be pushed ahead of a propelled vehicle, a frame structure provided at its forward end with a transverse plow blade, a single pivotal coupling centrally disposed with respect to the longitudinal vehicle axis and serving as a drive between the front of the vehicle and the rear of said frame, a support runner disposed at each side of said axis and spaced therefrom to maintain lateral stability of the frame about said coupling, and means for tilting the frame about said coupling to adjustably alter the height of said blade with respect to the road bed.

26. In a snow plow adapted to be pushed by a propelled vehicle, a plow frame structure provided with a side cutting blade, a single coupling means between the structure and the vehicle, adapted to flexibly connect said frame with the vehicle, runner means supporting said blade, and control means associated with said support means serving to adjustably raise or lower said blade.

In witness whereof, I have hereunto set my hand at Cortland, New York this 8th day of April, A. D. nineteen hundred and twenty-five.

LORAN ISBELL.
